SKIDWAY DOLLY

Paul J. Kordes, Milwaukee, Wis.

Application October 6, 1943, Serial No. 505,139

1 Claim. (Cl. 280—61)

My invention has for its primary object to provide a simple, low cost skid-way dolly equipment which can be readily adjusted in assemblage to meet all conditions for shifting heavy articles, such as machines, from place to place in shops, warehouses and the like, whereby material reduction of man power in such operations is made, and also to eliminate prevailing personal injury cases.

Another object of my invention is to provide a dolly unit embodying a skeleton frame with sets of rollers mounted upon fixed shafts supported on roller bearing spindles having loosely mounted keeper discs interposed between the roller spindles and juxtaposed walls of the frame, whereby friction is reduced between the rollers and frame and said discs at the same time perform their keeper function.

With the above and other minor objects in view, the invention consists in certain peculiarities of construction and combination of parts as will be fully set forth with reference to the accompanying drawing and subsequently claimed.

In the drawing:

Figure 1 represents a diagrammatic, plan view of a skid-way dolly equipment embodying the features of my invention.

Figure 2 is an enlarged, plan view of a dolly unit in accordance with my invention with parts thereof broken away and in section as indicated by line 2—2 of Figure 3.

Figure 3 is a vertical, sectional view of the dolly, the same being indicated by line 3—3 of Figure 2.

Referring by characters to the drawing, 1—1 indicates side plates, and 2—2 end plates of a rectangular frame. The end plates of the frame are reinforced and connected by a vertically disposed central division plate 3, which plate is also connected to the side plates 1 by a transversely disposed reinforcing plate 4.

The upper edges of the frame plates are connected by transversely positioned end back panels 5—5 and a central back panel 6 spaced from the panels 5, as clearly indicated by Figures 2 and 3. The frame is preferably fabricated from steel plates, which plates are secured by welding in the usual manner. It being understood that said frame is designed to resist very heavy load tonnage.

The side plates 1 are apertured and have brazed thereabout collars 7—7 for the reception of transversely disposed shafts 8—8, which shafts are fixed against rotation by locking pins 1' which pass through the collars and edges of the shafts.

The central division plate 3 is also apertured for receiving the shafts 8 whereby three supports are developed for said shafts.

Mounted upon each shaft 8 is a pair of centrally bored rollers 9 carrying anti-friction spindles 10. The rollers are of slightly less length than the distance between the plates 1 and 3, and loosely mounted directly upon the shafts are companion sets of discs 11.

10 Thus the rollers are provided with radial and end thrust anti-friction bearings to effectually eliminate heavy load strain in all directions, that might tend to spread the frame and jam the associated parts, it being understood that the 15 spindle ends are flush with the ends of the roller and abut the anti-friction discs.

In order to provide an adequate lubricating system for each roller, the ends of the shafts 8 are centrally bored for lubricating channels 12, 20 which channels have branches communicating with the bore of the roller and feed channels 12' that communicate with lubricating nipples 13 that are in threaded union with suitably aligned apertures in the frame collars 7. Hence, each roller 25 has a definite means of lubrication, which is quite essential in a heavy duty dolly of this type.

The back panels of each dolly unit are also provided with a plurality of calks 14 extending from the spaced panels for engagement with 30 skid-way timbers 15—15 as indicated in the diagrammatic view of Figure 1.

Having thus fully described a dolly unit, in their operation, as indicated in Figure 1 the timbers 15 are longitudinally positioned upon the back panels of a pair of dollies A—A and a machine or other article, indicated by the dotted lines B, which has previously been jacked up, is positioned over the dollies with the center gravity of said machine approximately centrally disposed with relation to said pair of dollies, whereby the said machine is properly balanced. Thereafter, the jacks supporting the machine are removed and its weight is supported by the wooden skid-ways 15. It being understood that 40 the tonnage of machines is such that it will cause the timbers to be embedded into the cleats, whereby rigidity, as to the position of said timbers with relation to the dollies, is insured. Thereafter the machines, by manual power, can 45 be readily rolled from place to place upon its supports and in actual practice over a period of months, this equipment has been satisfactorily used in large plants upon all types of hard floors or pavements, whereby the usual rollers used for 50 this general purpose are dispensed with and thus

a saving of time is had and accidents, due to positioning the rollers, are avoided.

It is obvious that the timbers and the associated dolly units can be positioned indefinitely, as to width, with relation to each other and also lengthwise. It is also apparent that the rollers of the dollies may be angularly disposed with reference to each other, whereby the load will more readily be moved in an arc of a circle.

What I claim as new is:

A dolly comprising a skeleton frame including vertically disposed apertured side plates, end plates connecting the same, a vertically disposed central division plate connecting the end plates having apertures aligned with the side plate 15

apertures, a vertically disposed reinforcing cross plate connecting the side plates and division plate, forming four skeleton cages, top panels extending inwardly from the end plates, connecting the side plates and division plate forming angle-iron reinforcements at the ends of the frame, a transverse centrally disposed panel extending in both directions from the cross plate and connecting the side plates to form a T shaped reinforcement for the frame, pairs of shafts extending through the division plate and side plate apertures, and pairs of rollers mounted upon each shaft, the same being housed within the frame cages.

PAUL J. KORDES.
